UNITED STATES PATENT OFFICE.

WILLIAM E. FRANK, OF ST. LOUIS, MISSOURI, ASSIGNOR TO FOSTER BROS. MFG. CO.,
OF ST. LOUIS, MISSOURI, A CORPORATION OF MISSOURI.

COILED-SPRING STRUCTURE.

Application filed February 10, 1922. Serial No. 535,562.

To all whom it may concern:

Be it known that I, WILLIAM E. FRANK, a citizen of the United States, residing at St. Louis, Missouri, have invented a certain 5 new and useful Improvement in Coiled-Spring Structures, of which the following is a full, clear, and exact description, such as will enable others skilled in the art to which it appertains to make and use the 10 same.

This invention relates to coiled spring structures such as are used in bed springs, vehicle seats and the like.

One object of my invention is to provide 15 a coiled spring structure in which the end coils of the springs of each row are connected together in a novel manner that permits the adjacent springs of a row to rock or turn freely relatively to each other without binding and without twisting or bending 20 the connections between said springs.

Another object is to provide a coiled spring structure in which the means for connecting the springs of a row together 25 and the means for holding the rows of springs in spaced relation are of such construction that they do not form sharp projections on one side of the structure.

And still another object is to provide a 30 coiled spring structure having the desirable characteristics above described that is easy to assemble and inexpensive to manufacture.

To this end I have devised a coiled spring 35 structure that is made up of a number of parallel rows of coiled springs, an integral portion on the end coil of each spring that is bent around or arranged in interlocking engagement with the end coil of an adjacent 40 spring in the same row, thus causing the springs of a row to be pivotally connected together, and tie wires or rods arranged transversely of said rows and connected to the springs in such a way that they hold the 45 rows of springs in spaced relation without interfering with the flexibility of the structure.

Figure 1 of the drawings is a top plan view of a coiled spring structure embodying my invention.

Figure 2 is an end elevational view of said structure; and

Figure 3 is a side elevational view of one of the tie wires.

55 I have herein illustrated my invention em-

bodied in a coiled spring structure made up of a number of rows of vertically-disposed, spiral springs A arranged in parallel relation to each other, but I wish it to be understood that it is immaterial whether the structure is made up of cylindrical or conical springs. At one side of the structure the end coils of the springs A are joined together in such a manner that the springs of each row are pivotally connected together and 60 the respective rows are held in spaced relation by tie wires or rods B that are arranged transversely of the rows. Preferably, the base coil or end coil of each spring is provided with a laterally-projecting loop 70 1 whose terminal portion 1^a is bent around the end coil of an adjacent spring of the same row, as shown in Figure 1, the terminal portion 1^a of each loop being doubled back upon itself and bent downwardly into or 75 below the plane of the coil which said terminal portion embraces, so as to form practically a closed eye on the laterally-projecting portion 1 of one spring that surrounds the end coil of an adjacent spring of 80 the same row. Accordingly, the springs of each row will be held spaced apart, but they are free to rock or turn relatively to each other without binding and without 85 bending or twisting the connections between said springs when a load is imposed on the structure.

The tie wires or rods B each consist of a straight piece of heavy wire provided at intervals with upwardly-projecting portions 90 2, preferably of substantially inverted V-shape in outline, that pass upwardly through the eyes formed by the bent over terminal portions 1^a of the laterally-projecting loops 95 1 on the end coils of the springs.

In assembling the parts of the structure the tie wires B are arranged transversely of or at right angles to the laterally-projecting loops 1 on the end coils of the springs and tangential to the portions of the end coils 100 around which the terminal portions 1^a of said loops are adapted to be bent. The terminal portion of each of said loops 1 is then bent around the end coil of an adjacent spring and doubled back over the projections 2 on the tie wire, thus causing the tie wire to be locked to two adjacent springs 105 of the same row by means of one of the projections 2 on said tie wire that projects through the bent over terminal portion of 110

the loop. It will thus be seen that in a structure of the character above described the bent over terminal portions of the laterally-projecting loops 1 on the end coils of the 5 spring not only serve to pivotally connect together the adjacent springs of each row, but they also serve to connect the tie wires B to the rows of springs, the tie wires being used merely to hold the rows of springs in 10 spaced relation.

A coiled spring structure of the design above described is exceptionally strong, on account of the way the adjacent springs of the various rows are interlocked with each 15 other and with the tie wires; it is free from sharp pointed projections at the points where the end coils of the springs and the tie wires are joined together, and it is easy to assemble and inexpensive to manufacture. 20

Having thus described my invention, what I claim as new and desire to secure by Letters Patent is:

1. A coiled spring structure, comprising 25 rows of coiled springs, tie wires arranged transversely of said rows, and a laterally-projecting portion on the end coil of each spring extending across the end coil of an adjacent spring of the same row and across 30 one of said tie wires, and having its terminal part doubled back so as to form an eye that surrounds said tie wire and said end coil.

2. A coiled spring structure, comprising 35 rows of coiled springs, a laterally projecting portion on the end coil of each spring having its terminal part doubled back so as to form an eye that receives the end coil of an adjacent spring in the same row, tie wires arranged transversely of said rows and extending through said eyes, and portions on 40

said tie wire that project into said eyes and thus prevent said tie wires from shifting transversely of said rows.

3. A coiled spring structure, comprising 45 rows of coiled springs, each of which is provided at one end with a laterally-projecting loop whose terminal portion is bent around an adjacent spring of the same row and doubled back upon itself so as to form an eye, and tie wires arranged transversely of 50 said rows in tangential relation to the end coils of the springs of said rows and embraced by the eyes on the loops on said springs.

4. A coiled spring structure, comprising 55 rows of coiled springs, each of which is provided at one end with a laterally-projecting loop whose terminal portion is bent around an adjacent spring of the same row and doubled back upon itself so as to form an eye, 60 tie wires extending transversely of said rows through the eyes on the loops on said springs, and projections on said tie wire positioned in said eyes to prevent said tie wires from moving transversely of said rows. 65

5. A coiled spring structure, comprising 70 rows of coiled springs, tie wires arranged transversely of said rows in tangential relation with the end coils of the springs in said rows, integral, laterally-projecting loops on the end coils of said springs, each of which has its terminal portion bent around the end coil of an adjacent spring of the same row and doubled back over one of said tie wires so as to form an eye which surrounds said 75 end coil and tie wire, and means on said tie wires that co-operate with the eyes in said loops to prevent the tie wires from shifting transversely of said rows.

WILLIAM E. FRANK.
